CLAIM

The ornamental design for a controller shell, as shown and described.

DESCRIPTION

FIG. 1 is a perspective view of a controller shell showing my new design;

FIG. 2 is a front view thereof;

FIG. 3 is a back view thereof;

FIG. 4 is a left view thereof;

FIG. 5 is a right view thereof;

FIG. 6 is an enlarged top view thereof; and,

FIG. 7 is an enlarged bottom view thereof.

The broken lines shown on the drawings depict portions of the controller shell that form no part of the claimed design.

1 Claim, 7 Drawing Sheets
